UNITED STATES PATENT OFFICE.

HARRY N. CAIN, OF CLEVELAND, OHIO, ASSIGNOR TO THE DONLEY BROTHERS COMPANY, OF CLEVELAND, OHIO, A CORPORATION.

FIREPLACE DAMPER.

1,415,522.

Specification of Letters Patent. Patented May 9, 1922.

Application filed May 4, 1918. Serial No. 232,432.

To all whom it may concern:

Be it known that I, HARRY N. CAIN, of Cleveland, in the county of Cuyahoga and State of Ohio, have invented new and useful Improvements in Fireplace Dampers, of which the following is a specification.

This invention relates to dampers for closing chimney flues above fireplaces, and for regulating the draft thereof.

- 10 The prime object of the present invention is to provide convenient and readily accessible means for adjusting and positively retaining a fireplace damper at any desired degree of angular opening, and for closing the damper when the fireplace is not in use. Further objects are to produce a damper and regulating device therefor adapted to close by the action of gravity; which may be easily removed from the fireplace for the purpose of cleaning the chimney flue, or for repairs; which will operate freely without clogging; and which is simple and inexpensive to construct and install.

25 Minor objects will become apparent from the following description of a preferred form of my invention, reference being had to the accompanying drawing, in which—

Fig. 1 is a sectional elevation of a damper and part of a fireplace and chimney.

30 Fig. 2 is a plan view, partly broken away, of the damper and frame.

Fig. 3 is plan view,

Fig. 4 is a side elevation, and

35 Fig. 5 is an end view of the adjustable damper regulator.

Fig. 6 is a side view like Fig. 4 showing the pawl disengaged from the ratch of the regulator.

40 The reference letter *a* indicates the upper part of a fireplace opening, and *b* the lower end of a smoke flue therefor, substantially as usually constructed in a chimney *c* of a house. The damper *d* is arranged to close, or to open to any desired degree the throat, or contracted communicating passage between the said fireplace and flue.

45 The damper frame, preferably of cast iron, comprises a body portion *e* shaped like a hollow wedge, its open bottom conforming to the shape of the top of the fireplace, its sides and ends inclined inwardly as shown, and a surrounding horizontally projecting flange *f* forming its base. The ends of the flange *f* are built into the brickwork of the chim-

ney, the rear part of it rests upon the shelf 55 *g* at the bottom of the flue, and the front portion of said flange, together with the front inclined side of *e*, spans the fireplace *a* like a lintel supporting the roof thereof.

The rearward inclined face of the damper 60 frame body *e* rises but slightly above the flange *f*, and is provided with a pair of outwardly and upwardly projecting ears *h*—*h*, one near each end, forming with the said face hinge sockets adapted to support the 65 lower edge of the flat damper door *d*. Upright stop lugs *i*—*i* on the ends of the frame body *e* respectively prevent the damper *d* shifting endwise out of place. Thus a large 70 rectangular flue opening *j* is formed in the rearward slope of the frame *e*, and adapted to be tightly covered by the swinging damper *d*.

A regulator rack bar *r*, straight and of 75 rectangular section, is hinged at its lower end, preferably by a cotter pin *k*, between a pair of ears *l* depending from the damper frame *e*, and is provided with ratch-teeth *t* upon its upper edge. At the upper end of the bar *r*, and diagonally opposed to each 80 other, upright standards are erected and their terminations connected across as at *m*, Figs. 3, 4 and 5; thus forming a closed guideway about a rectangular aperture forming a loop through which a pawl-bar *p* 85 may slide. The diagonal disposition of the guideway *m* both permits the casting to be made without employing a core, and serves to prevent the aperture therein becoming clogged with soot and other products of combustion.

The pawl-bar *p*, which is also straight and of substantially rectangular section, is hinged at its upper end, preferably by a cotter pin *n*, between a pair of ears *o* projecting from the under face of the damper *d*; both the bars *r* and *p* being hinged to swing vertically. The lower end of the bar *p* is bent downward and beveled to a thin edge, as at *q*, so as to form a detent fitted 90 to engage the ratch-teeth *t* when sliding downward.

A guideway *u* for the bar *r* depends from the detent end of the bar *p*, and is formed similarly to the guideway *m*, and for the 105 same reasons, having diagonally disposed side bars connected at their lower ends; but the connection in this case is enlarged to

form a ring-shaped handle *s* beneath the guideway *u*, by which the damper may be operated. Both the guideways *m* and *u* are made somewhat longer vertically than the widths of the respective bars *p* and *r*; so that lifting the handle *s* serves to raise the said bars from their normal parallel positions shown in Fig. 4 sufficiently to disengage the pawl *q* from the rack teeth *t*, as in Fig. 6. When hung in place, the weight of the regulating device compels contact between the bar *p* and the upper part of the guideway *m*, and forces the detent *q* into the teeth *t*.

To operate the damper to regulate the draft of a fire, an ordinary hook-ended poker may be used to engage the handle ring *s*, as indicated by dotted lines in Fig. 1; an upward push disengaging the pawl *q* from the ratch-teeth *t*, and opening the damper *d* if continued; or said damper may be permitted to close to any desired position when the said handle ring is raised and drawn, or allowed to slide forward, the bars *p* and *r* locking together by gravity when the lifting action is discontinued.

Obviously the hinge means of the damper *d* will not become clogged with droppings from the chimney flue; and by removing the cotter pin *h* both the damper *d* and the regulating bars *p* and *r* may be lifted and re-

moved from the chimney for the purpose of cleaning or making repairs.

I further point out and distinctly claim as my invention—

1. A regulating device of the class described comprising a pair of substantially parallel bars, the upper bar having a detent-shaped end with a guideway loop for the lower bar and a handle depending therefrom, and the lower bar being provided with ratch-teeth engageable with said detent to prevent shortening of the device and having a guideway loop for the upper bar mounted upon its inner termination. 40 45

2. A regulating device for dampers comprising a pair of substantially parallel bars, rack and pawl means adapted to interlock said bars together, and a guideway on each of said bars looped about an aperture to slidably receive the other bar, said guideways being offset at right angles to the bars and diagonally disposed transversely thereof respectively. 50

In testimony whereof I affix my signature 55
in the presence of two subscribing witnesses,
at Cleveland, Ohio, this 27th day of April,
1918.

HARRY N. CAIN.
